(57) **CLAIM**

The ornamental design for a fishing lure, as shown and described.

DESCRIPTION

FIG. 1 is a right side perspective view of the fishing lure according to an embodiment;

FIG. 2 is a right side view of the fishing lure illustrated in FIG. 1;

FIG. 3 is a top view of the fishing lure illustrated in FIG. 1; FIG. 4 is a bottom view of the fishing lure illustrated in FIG. 1;

FIG. 5 is a front view of the fishing lure illustrated in FIG. 1; FIG. 6 is a rear view of the fishing lure illustrated in FIG. 1; and,

FIG. 7 is a cross-sectional view of the fishing lure illustrated in FIG. 1 taken along line 7-7 in FIG. 2. The broken lines immediately adjacent the shaded areas represent the bounds of the claimed design while all other broken lines are directed to environment and are for illustrative purposes only; the broken lines form no part of the claimed design.
